DESIGN FOR A BAFFLE BOARD PANEL FOR RADIOS OR THE LIKE

Arthur C. Haggstrom, Rockford, Ill., assignor to
E. H. Scott

Application March 3, 1941, Serial No. 99,299

Term of patent 3½ years

To all whom it may concern:

Be it known that I, Arthur Chas. Haggstrom, a citizen of the United States, residing in Rockford, in the county of Winnebago and the State of Illinois, have invented a new, original, and ornamental Design for a Baffle Board Panel for Radios or the like, of which the following is a specification, reference being had to the accompanying drawing forming a part thereof.

The figure is a perspective view of a baffle

board panel for radios or the like showing my new design.

The panel has an unappreciable thickness and the other side, not shown, is substantially the same as the side shown.

I claim:

The ornamental design for a baffle board panel for radios or the like, as shown and described.

ARTHUR CHAS. HAGGSTROM.
